ATTORNEY.

32 and the bottom of the recess 31. The said switch 27 has leads 34 and 35 extending therefrom, through holes in the block 5, to terminals 36 and 37 respectively.

As shown in FIG. 8, a motor 38 is connected in a main electric circuit 39 through a switch 40. Said circuit has a suitable transformer 41 leading to a low voltage circuit 42 that is controlled by a plurality of the switches 27, one for each shuttle in the loom to operate a relay 43 to the switch 40 and thereby de-energize the motor 38 and stop the loom.

The operation of said stop motion device is as follows:

When the filler thread 12 is under tension, as during the normal operation of the loom, the utilized spring 14 will be held by said filler thread in its stretched condition and said spring will pull the plunger 21 inwardly and compress the spring 26, as clearly shown in FIG. 6. When the filler thread is exhausted, or upon its being broken, the spring 14 will be released so that it will contract and thereby release the plunger 21. Said plunger will then be moved by the spring 26 to its normal position shown in FIG. 7. Then, as the shuttle passes through the groove 32 in the block 7 and the plunger 21 passes by the reed switch 27, the said plunger will magnetically cause the reed 30 to contact the bar 29 and thus close the said switch to energize the circuit 42 and operate the relay 43 to open the switch 40 and thereby deenergize the motor 38 and stop the loom.

It will be understood that the spring 26 is weaker than the pull from the spring 14 so that it will yield under the said pull to allow the spring 14 to move the plunger 21 to its retracted position shown in FIG. 6, in which position it is stopped by abutment of the stop sleeve 25 against the wall 23. When the pull is released, the spring 26 will expand and thus return the plunger to its normal position in which it will operate as above described to close the electric switch 27 and stop the loom.

In order to quickly determine which of the switches 27 has been operated in looms where a multiplicity of shuttles are used, I may provide, for each of said switches, a self locking relay 44, as shown in FIG. 8; said relay having an indicating light 45 and a switch 46 with a latch 47.

When the switch 27 is momentarily closed, by movement of the magnet plunger 21 to the position shown in FIG. 7, the relay 44 will close the switch 46 and the latch 47 will keep said switch closed. This will energize the indicating light 45 and thereby provide lasting indication as to which of the switches 27 was operated by its respective plunger 21 and stopped the loom. After the cause of the stoppage has been attended to, the switch 46 may be returned to normal by manually tripping the latch 47.

I claim:

1. In a loom including a shuttle block, a shuttle moveable in said block, a quill mounted in said shuttle and carrying a filler thread thereon, and a tension spring for tensioning said thread; a stop motion mechanism including an electric switch mounted in said block and controlling the operaiton of said loom, and an operating plunger within said shuttle and connected to said spring for operating said switch to cause stoppage of said loom.

2. The loom set forth in claim 1 wherein said spring upon being stretched is adapted to move said plunger from a normal to a retracted position and said switch is operable by said plunger when in the normal position.

3. The loom set forth in claim 1 wherein said plunger is slideable within the shuttle into retracted and normal positions and secured to the tension spring whereby when said spring is stretched the plunger is pulled into the retracted position and when the spring is contracted the plunger is released, and a separate spring for returning said plunger to the normal position upon being released by the tension spring.

4. The loom set forth in claim 1 wherein said plunger is out of contact with said switch and magnetized whereby when in the normal position and moved past the switch said plunger will operate said switch magnetically.

5. For a loom including a shuttle moveable in a shuttle block and having a quill with a filler thread thereon, a tensioning spring for tensioning said thread, an operating plunger moveable withi said shuttle to retracted and normal positions and secured to said tensioning spring; said spring when stretched being capable of pulling the plunger to the retracted position and to release said plunger upon being contracted, a separate spring adapted to move the plunger to the normal position upon it being released, and a switch mounted within said block and operable by said plunger when in the normal position to cause stoppage of said loom.

10 6. For a loom, the subject matter set forth in claim 5 wherein said plunger is magnetized and entirely enclosed within the shuttle and is adapted to operate said switch magnetically.

20 7. For a loom, the subject matter set forth in claim 5 wherein said switch is contained within the shuttle block and shielded from the exterior of said block by a wall portion of the block material and adapted to be magnetically operated upon the plunger passing by said wall portion 25 while in the normal position.

25 8. In a loom including a shuttle block, a shuttle moveable in said block, a quill mounted in said shuttle and carrying a filler thread thereon, and a tension spring moveable in a hole in said shuttle for tensioning said filler thread; a stop motion mechanism including a magnetically operable switch mounted in said block for controlling the operation of said loom, a sleeve inserted in said hole substantially flush with the surface of the shuttle, a magnetized plunger moveable in said sleeve to retracted and normal positions, abutment means between said plunger and sleeve for locating the plunger in the retracted position, the said tension spring being secured to said plunger and adapted when stretched to retain the plunger in retracted position and when contracted to release said plunger, and a separate spring within said sleeve adapted to return the plunger to its normal position upon being released by the tension spring whereby as the said shuttle moves in the shuttle block and the plunger is carried past the switch in said block, the said switch will be operated by the plunger to cause stoppage of the loom.

30 9. For a loom, the subject matter set forth in claim 8 wherein the end of said sleeve is closed to shield the plunger from the exterior of the shuttle.

35 10. For a loom, the subject matter set forth in claim 8 wherein the said magnetically operated switch is mounted in a recess in the back of the shuttle block and shielded from the front surface of said block by a thin wall of the block material.
